US0D1023695S

(12) **United States Design Patent** (10) **Patent No.:** **US D1,023,695 S**
Sell (45) **Date of Patent:** **** Apr. 23, 2024**

(54) **KITCHEN UTENSIL**(71) Applicant: **Forrest Sell**, Epsom, NH (US)(72) Inventor: **Forrest Sell**, Epsom, NH (US)(**) Term: **15 Years**(21) Appl. No.: **29/902,610**(22) Filed: **Sep. 14, 2023****Related U.S. Application Data**

(63) Continuation of application No. 18/121,818, filed on Mar. 15, 2023.

(51) **LOC (14) Cl.** ..... **07-06**(52) **U.S. Cl.**USPC ..... **D7/685**CPC ..... **A22C 21/066** (2013.01)(58) **Field of Classification Search**

USPC D7/368, 669, 680-696, 393, 395; 294/106, 118, 119
